J. F. BRICKLEY, OF WINCHESTER, INDIANA.

Letters Patent No. 84,991, dated December 15, 1868.

IMPROVEMENT IN PUMPS.

The Schedule referred to in these Letters Patent and making part of the same.

To all whom it may concern:

Be it known that I, J. F. BRICKLEY, of Winchester, in the county of Randolph, and State of Indiana, have invented a new and useful Improvement in Pumps; and I do hereby declare that the following is a full, clear, and exact description of the same, reference being had to the annexed drawings, making part of this specification, in which—

Figure 1 is an elevation of my improved pump, and

Figure 2, a sectional elevation of one of the pump-plungers, with its rod, valve, and the valve-regulating mechanism.

The same letters indicate identical parts in both figures.

This invention relates to an improvement in pumps; and

It consists, first, in a water-induction regulator, and secondly, in the combination and arrangement of the parts, as will be hereinafter described.

A is the main or principal stock of the pump, the upper and lower sections of which are of wood, and are constructed in any suitable manner, and have the usual appliances connected therewith, consisting of a check-valve in the lower section to prevent the water from running down and out of the stock after it has once been filled, while the upper section contains a bucket, having a valve, which bucket is attached to a rod, which connects it to the handle.

B is the central section of the pump-stock, which may be of iron, brass, porcelain, glass, or any suitable material, to form a smooth cylinder for the bucket to work in.

C is an additional or second pump-cylinder or stock, arranged by the side of the first, and so arranged that its bucket or plunger may be worked by the same handle which works the first, as clearly shown in fig. 1 of the drawings. This stock is supplied with the usual appendages of an independent pump, except that it has not a check-valve in its lower end, the valve in the lower end of A answering for both pumps; the supply of water for this pump being drawn through the connecting-pipe a, and discharged, through pipe c, into stock A, from whence it passes, through connecting-pipe b, into the delivery-pipe E.

D is a column, of wood, which may, if desired, extend to the bottom of the well, and may serve as a support for the pump to rest upon. This column has a hole bored from its top downwards, a distance of one-half its length, more or less, and it also has holes bored longitudinally from one of its sides inwards, to communicate with the vertical passage, which latter passages are ordinarily closed with spigots or plugs of wood, but they may be used as water-induction passages, when desired.

E is a delivery-pipe, which is arranged vertically alongside of the two pump-stocks A and C, and which communicates with the first, or A, by means of a connecting-pipe or passage, b, and with the second, or C,

by means of the pipes c, which convey the water therefrom to A, from which it is delivered to pipe E through connecting-pipe b. This pipe extends nearly or quite to the top of pump A, and its orifice is controlled by a spigot or by a plug of wood, which closes it air-tight, when the pumps are used only as lifting-pumps, which is to be opened or removed when it is desired to use them both as lifting and forcing-pumps, at which times a hose may be applied to the end of pipe E, to conduct the water to any desired point, or other pipes may be connected thereto, through which the water may be conveyed.

F is a flexible hose or pipe, which is made of India rubber, gutta-percha, leather, or any other suitable material, and which serves generally as the induction-pipe to the pump.

To the upper side of this pipe or hose, as it is extended at a right angle to the pump-stock, is attached, by means of a chain or wire, a float, G, which is of sufficient size and buoyancy to prevent the hose from sinking; while to the under side of said hose is attached, in a similar manner, a weight, H, of sufficient size to prevent the mouth of said hose from ever rising above the surface of the water.

The object of the above-described induction-pipe being to provide means for drawing the purest and best water from what are termed sulphur wells, by always taking it from within one to two feet of the surface thereof.

I is the handle of the pump, which is of ordinary construction, but which is arranged to operate the buckets of both of the pump-stocks.

K is a metallic rod, which is placed vertically by the side of the rod which connects the buckets with the operating-handle, and which is secured thereto by means of staples.

Near the upper end of this rod a screw is formed, which works through a nut secured to the rod, and above said screw, and so arranged as to project above the pump-stock, a handle is formed or secured for turning said rod.

When it is desirable to convert the pump into a forcing as well as a lifting-pump, this rod is screwed downwards until its lower end rests upon the valve L, on the top of the bucket M, thus holding the valve to its seat, by which means the water is prevented from rising up through the bucket, and the pump is converted into a forcing-pump, by which water may be forced through delivery-pipe E, as above described.

L, fig. 2, shows the valve, and M, in the same figure, the bucket; the same figure showing clearly the above-described arrangement of screw-rod; and it is proper to say that both of the plunger-rods are provided with the same means for pressing their valves upon their seats, and also that by regulating the lift or rise of such valves, the amount of water raised can be regulated when the pump is used as a lifting-pump only.

Having thus described my invention,
What I claim, and desire to secure by Letters Patent, is—

1. The combination and arrangement of pump-stocks A C and delivery-pipe E, substantially as and for the purpose described.

2. The arrangement of the stocks A and C and the delivery-pipe E, connecting-pipes *a*, *b*, and *c*, with reference to the valve-regulating rod K, by which the

pump may be converted from a lifting-pump only into a lifting and forcing-pump, substantially as described.

In testimony whereof, I have signed my name to this specification, in the presence of two subscribing witnesses.

J. F. BRICKLEY.

Witnesses:

J. A. MOORMAN,
C. H. STANLEY.
